UNITED STATES PATENT OFFICE.

J. EDWIN GILES, OF HAZLETON, PENNSYLVANIA.

ELECTRICAL EXTENSION-BRACKET.

SPECIFICATION forming part of Letters Patent No. 293,318, dated February 12, 1884.

Application filed September 8, 1883. (No model.)

To all whom it may concern:

Be it known that I, J. EDWIN GILES, of Hazleton, in the county of Luzerne and State of Pennsylvania, have invented certain new and useful Improvements in Electrical Extension-Brackets; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My improvement relates to electric-lamp fixtures for lighting from a side wall or from a ceiling.

The object of my invention is to simplify the construction of fixtures, to lessen the cost of first construction, and to render the electrical communication such that it may not require an expert to make the connections between the main conductor and lamp or repair parts accidentally damaged.

In my improvement in side-wall fixtures I use a pivoted or jointed bracket, either fastened to the wall or screwed to an existing gas-pipe in the same manner that gas-brackets are now attached, permitting, if required, the electrical conductors to be brought through the gas-pipe and coupled up to a tube and pin within the lower part of the swiveling device by simple hooks formed by the ends of the conductors being bent. This tube and pin, insulated from each other and from the swiveling device, pass through to a chamber within the upper part of the swiveling device, where they communicate with other conductors by simply hooking or twisting.

Secured to the upper part of my bracket-joint or swivel is an extension-arm or lamp-support. In my improved extension-bracket arm I use an inner and outer tube, and although the positions of these tubes can be reversed without detriment to my improvement, I prefer, because of increased strength, to use the outer or largest tube in connection with the swivel. In some cases I use but one tube, replacing the inner tube by a bar of any suitable non-conducting material—such as wood, vulcanite, or other substance—to be of the same shape as the outer tube, with an unbroken surface, and to be stiffened by inserting metal

tubes, that shall also serve as current-conductors. Where two tubes are used—an outer and an inner—I insert within the inner tube two small tubes, to serve as current-conductors and to guide metal rods that are constantly in rubbing electrical contact, thus dispensing with contact-strips, springs, &c. These small tubes are placed within the inner tube, and a semi-liquid insulating material—such as asphalt or a compound thereof in a heated state—is poured in, thus insulating the small tubes from each other and from the containing tube.

My improved lamp-switch for completing the circuit with the lamp consists of a thumb-key at the bottom or finger-lever at the side, or both, of the switch-box or lamp-holder, depending on the use to which the lamp is put or whether it shall be mounted on the end or top of the bracket.

My circuit closing or breaking device consists of the finger-lever operating against one or between two metal pieces, preferably strips slightly bent, so as to keep the lever in out of contact with a metal pin or plate. The metal springs and pin are respectively connected with a conductor and lamp.

My improvement in vertical extension-fixtures is, in all important features, essentially the same as my improved wall extension-bracket, excepting that in the hanging-lamp fixture, to overcome the weight of the lower tube or bar, lamp, &c., I provide a packing-box filled with any suitable material, thus producing sufficient friction to sustain the weight of the tube or bar, lamp, &c. This vertical extension-fixture can be screwed to an existing gas-pipe or attached to the ceiling; or it can be a part of and carrying a lamp or lamps of a chandelier.

I do not confine myself to two internal conductors in extension-fixtures, as where the tubes or metals forming the extension device constitute one conductor, then but one internal conductor will be necessary.

My invention further consists of certain other features of construction, all as hereinafter described and claimed.

Reference is to be had to the accompanying drawings, forming a part of this specification, in which similar letters of reference indicate corresponding parts in all the figures.

Figure 1 is a side view, in section, of a com-

plete wall extension-bracket, with swivel-joint and lamp-switch. Fig. 2 is an enlarged plan of the lamp-switch. Fig. 3 is a ceiling or drop extension-fixture in section. Fig. 4 is an enlarged section of bar *c* and tube *f*.

A is a base or lower part of a swiveling device, provided with means for securing to a gas pipe or fixture, or attaching to the wall.

A' is the upper part of the swiveling device, fitting over *A*, and forming a movable joint. *A* and *A'* are secured together by a nut, *b*, or a screw, *b'*, working in a groove in *A*.

Through the projecting swivel of *A*, and insulated therefrom, passes a tube, *b*², through which and insulated therefrom passes a metal pin, *b*³. To complete the insulation, washers *b*⁴—top and bottom—are used. The pin and tube are held in position by friction or other means. Conductors *b*⁴ *b*⁵ are hooked on the tube *b*², and *b*⁵ *b*⁶ are hooked on the pin *b*³. The conductors *b*⁴ *b*⁵ and *b*⁵ *b*⁶ are coiled or crooked at any part of their length, thus giving sufficient tension to keep the hooks in place and afford good electrical contact. *a* *a'* are caps for covering the upper and lower contact-chambers. The conductors are simply bent to form hooks; or they may be bent to form an eye that can be slipped over the tube and pin. Where the body of *A* or *A'* or any part thereof constitutes one conductor, then but the insulated pin and one internal conductor will be necessary.

f is a tube of metal or other material, in which slides a bar of wood or other non-conducting material, *c*.

*b*⁶ *b*⁶ are metal tubes, running longitudinally through *c* without disturbing the surface of *c*. *b*⁶ *b*⁶ are also current-conductors.

*b*⁷ *b*⁷ are metal rods or bars secured to but insulated from tube *f*, and passing into tubes *b*⁶ *b*⁶, bars *b*⁷ being slightly sprung apart before being inserted in tubes *b*⁶. The tubes and bars will remain in constant rubbing and electrical contact. Inner tube, *f'*, can be slipped over bar *c*, as shown in Fig. 3; or the tubes *b*⁶ may be placed within tube *f'*, but electrically separated therefrom and from each other, when an insulating material that will harden is poured in, thus fixing the tubes and insulating them from each other.

*f*² shows a packing-box attached to the lower end of the tube *f*, which I employ in vertical extension-fixtures to overcome the weight of the lower bar or tube, lamp, &c. This box may be filled with any suitable packing material to produce sufficient friction to sustain said weight.

B is a switch-box or lamp-holder, preferably of non-conducting material, and is surrounded by a band, to which is secured a plug or sleeve for connecting with a bracket or a pipe or rod.

g is a thumb-key secured to plug *g'*.

*g*² is a projecting piece or finger-lever secured to *g*.

*g*³ is a metal strip or spring, and bearing against *g*². Two strips can be used—one above and one below the lever.

*g*⁵ is a pin or equivalent, against which the lever bears when the circuit is closed. The shape of strip *g*³ is formed to keep the lever in contact with *g*⁵ or out of contact, as desired.

*A*³ is a screw-socket for connecting a vertical extension-fixture with a gas-pipe, which can be replaced by any desired form of fastening.

*f*² is a packing-box for producing sufficient friction on tube or bar *f*' to sustain the weight of the suspended fixture, lamp, &c.

*f*³ is a socket, open through for convenience of connecting conductors either by hook, eye, or twist. The open end is closed by plug *h*. Pipes *b*⁸ are secured to *f*³ and carry lamp, shade, &c., also convey the conductors to the switch and lamp.

Having thus described my invention, I claim as new and desire to secure by Letters Patent—

1. In electrical extension-fixtures, the combination of the swiveling device consisting of the parts *A* *A'*, arranged to rotate, and secured together as shown, with the tube *f*, carrying conductors *b*⁷, and bar *c*, of insulating material, having tubes *b*⁶, extending longitudinally therethrough, and sliding in said tube *f*, all substantially as described.

2. In electrical extension-fixtures, the combination of the swiveling device consisting of the parts *A* *A'*, each having cap *a'*, with tube *b*², pin *b*³, passing through said tube and insulated therefrom, and electric conductors connected with said tube and pin, substantially as shown and described.

3. The combination of the swiveling device, tube *f*, carrying conductors *b*⁷, and bar *c*, having tubes *b*⁶, extending therethrough, all as described, with tube *b*², pin *b*³, and conductors *b*⁵ *b*⁶, all substantially as shown and set forth.

4. In electrical brackets, the combination, with a joint or swiveling device maintaining electrical communication, of a tube secured thereto inclosing conductors, and an extension-bar of non-conducting material carrying tubes for continuing electrical contact in extension-arms, substantially as described.

5. In electrical extension devices, the combination of two naked bars secured as shown, with a bar or tube containing two metal tubes for receiving said naked bars, substantially as shown and described.

In testimony that I claim the foregoing as my own I hereunto affix my signature in presence of two witnesses.

J. EDWIN GILES.
